UNITED STATES PATENT OFFICE.

JAMES A. CAMPBELL, OF NEW ORLEANS, LOUISIANA.

BARREL-HEAD.

SPECIFICATION forming part of Letters Patent No. 399,494, dated March 12, 1889.
Application filed November 17, 1888. Serial No. 291,177. (No model.)

To all whom it may concern:

Be it known that I, JAMES ALEXANDER CAMPBELL, a citizen of the United States, residing at New Orleans, in the parish of Orleans and State of Louisiana, have invented certain new and useful Improvements in Barrel-Heads; and I do declare the following to be a full, clear, and exact description of the invention, such as will enable others skilled in the art to which it appertains to make and use the same.

My invention relates to improvements in barrel-heads; and it has for its object to provide devices whereby the head of a barrel may be put in and tightened up to any desired degree and also taken out without either injuring the head or disturbing the hoops, so that the same head may be used any number of times. These objects I accomplish by the means shown and illustrated in the accompanying drawings, in which—

Figure 1 is a plan view of a barrel, showing my improved head in position to receive the fastening devices. Fig. 2 is a similar view showing the fastening devices in position. Fig. 3 is a plan view of the wedges removed. Fig. 4 is an edge view of the same. Fig. 5 is a plan view of a modification. Fig. 6 is an edge view thereof. Fig. 7 is a view of the same, showing the securing-plate. Fig. 8 is a longitudinal sectional view of the latter, and Fig. 9 is a plan view of the small wedge when made of wood with a metal plate attached.

Referring by letter to the said drawings, L M indicate the segmental sections of a barrel-head, which may be such as those usually employed, and P indicates an intermediate section of the head. This latter section has one of its longitudinal edges cut tapering, as shown at a, for the greater portion of its length and terminates in an offset, b, for the reception of the small wedge, as will be presently explained.

A indicates the large wedge, which may be of wood, metal, or other suitable material. This large wedge has its smaller end beveled from opposite sides, so as to adapt it to enter the chine-groove of a barrel. This long wedge is also provided with a desirable number of cross strips or flanges, C, which when in proper position will bear upon the upper side of the intermediate section and the adjacent

chine-section, respectively. The large end of this large wedge is beveled, as shown at G, for a purpose which will be presently explained.

I have illustrated several forms of the long wedge.

In some cases I form two transverse grooves, I, in the long wedge near its larger end to facilitate the driving of the same in position and remove it when desired.

In making the wedge of wood a metallic plate, K, may be employed, which is provided with a lug on its upper side to receive the impact of the driving implement. This plate is secured to the large wedge, preferably near its large end, by nails or other suitable fastening devices, which will resist the strain of the driving implement.

B indicates the small wedge. This wedge, which is preferably made of metal, is of a slightly greater width than that of the large wedge A, and is provided at its inner or abutting end on its upper side with a flange, D. In making this small wedge of metal the flange may be formed entire and provided with perforations at opposite ends, as shown, so that when seated it may be secured to the sections of the barrel-head.

When the wedge B is made of wood, a plate, H, is secured to it, so as to extend beyond its inner end, in which case it may be fastened to the head-sections in a manner similar to and serve every function of the flange D. This wedge B is tapered from opposite sides at its outer end, which coincides in curvature with that of the barrel-opening, and is adapted to enter the chine-groove thereof.

The opposite or inner end of the wedge B is beveled from below upwardly, so as to engage the corresponding bevel, G, of the large wedge A. When making the large wedge of wood, a plate, K, which serves the functions of the cross-strips C in the metal wedges, may have a lug on its upper side, as better shown in Figs. 7 and 8, whereby it may be driven in and out of position.

In operation, after the sections of the barrel-head have been placed in position the large wedge A is placed between the tapered edge of the middle head-section and the adjacent edge of the segmental section and driven until its smaller tapering end enters the chine-

groove of the barrel. The smaller wedge, B, is then placed in the remaining portion of the opening between the sections of the head, when one or two slight blows of a hammer or other implement will properly seat it, so that one end will enter the chine-groove and the opposite end bear snugly against the beveled edge G of the large wedge, when screws or other fastening devices may be applied to the cross strips or flanges.

Having described my invention, what I claim is—

The combination, with the sections of a barrel-head such as described, of the large wedge

having one end adapted to enter the chine-¹⁵ groove of a barrel and its opposite end beveled, and a small wedge having one end adapted to enter the chine-groove, its opposite end beveled to engage the bevel of the large wedge, and provided with a flange overhanging the said beveled end, substantially as specified.

In testimony whereof I affix my signature in presence of two witnesses.

JAMES A. CAMPBELL.
